TOILET SEAT

Rose Liebling, Atlanta, Ga.

Application August 6, 1948, Serial No. 42,880

5 Claims. (Cl. 4—234)

1

This invention relates to a toilet seat and an object of the invention is to provide a supplemental seat associated with a cover for coaction with the regular seat, said supplemental seat being adapted for use for children.

It is also an object of the invention to provide a toilet seat cover with which is adapted to nest a supplemental seat and wherein the supplemental seat carries means adjustable into and out of working position to provide a back and arm rest when desired.

A further object of the invention is to provide a toilet seat including an element, which when in one position partly surrounds the seat and when in a second position provides a back and arm rest.

The invention consists in the details of construction and in the combination and arrangement of the several parts of my improved toilet seat, whereby certain advantages are attained, as will be hereinafter more fully set forth.

In order that my invention may be better understood, I will now proceed to describe the same with reference to the accompanying drawings, wherein:

Figure 1 is a fragmentary view in perspective of a toilet seat constructed in accordance with an embodiment of the invention;

Figure 2 is an enlarged sectional view taken substantially on the line 2—2 of Figure 1;

Figure 3 is an enlarged fragmentary view in side elevation showing a front support for the back rest and side arms, a secured position of certain of the parts being shown by broken lines;

Figure 4 is an enlarged fragmentary rear elevational view showing the means herein embodied for supporting raised the rear portion of the back rest and side arms; and

Figure 5 is an enlarged sectional view taken substantially on the line 5—5 of Figure 3.

In the embodiment of the invention as illustrated in the accompanying drawings, S denotes a conventional type of toilet seat of an adult size and which has associated therewith a cover C hingedly connected therewith in a conventional manner. The cover C is preferably made of a plastic material and is hollow with the inner face wall 1 thereof formed to provide a continuous groove 2 of such dimensions to snugly receive and house a supplemental seat A. The seat A is of a size for infants or small children and when in use rests from above on the seat S with the central opening a of the seat A in required register with the central opening 3 of the seat S.

2

The seat A is also preferably made from a plastic material and has extending outwardly from the rear thereof the hinge straps 4 which operatively engage the pintle 5 comprised in the hinge connection between the cover C and the seat A. The length of the straps 4 are such to assure the seat A being received in the groove 2 and also to assure proper placing of the seat A upon the seat S.

10 The seat A substantially midway of its front and rear is provided in its outer marginal portions with the transversely opposed substantially parallel elongated recesses 6 in the forward portions of which are pivotally held, as at 7, the lower or inner extremities of the rigid arms 8 of required length. These arms 8 are preferably flat and the pivotal mountings 7 are preferably at the forward end portions of the recesses 6. When in their lowermost positions the arms 8 are housed 20 within the recesses 6.

15 The arms 8 at substantially their transverse centers are provided with the slots 9 extending a major distance therealong. The slots 9 are substantially duplicate as to form and dimensions and have the inner or lower end equidistantly spaced from their pivotal mountings 7. The outer end portions of the slots 9 are provided with the short lateral extensions 10 terminating in the relatively shallow pockets 11 disposed inwardly of 30 and, of course, at similar sides of the slots 9.

25 Coacting with the seat A is the member R which constitutes a back rest and arm support. The member R is preferably of plastic and substantially U-shaped in form and of such dimensions as to snugly surround the rear portion of the seat A when the member R is lowered. The intermediate or base portion 12 of the member R is on an outward curvature in accordance with the rear curvature of the seat A and said portion 35 12 is immediately adjacent to the lower portion of the rear side edge face of the seat A when the member R is lowermost. In such position the top surface of the member R is below the top surface of the seat A and the groove 2 is of a width to readily receive and house the lowered member R when the seat A is swung up into said groove 2.

30 The free extremities of the side arms 12a of the member R are forwardly disposed and at a desired point inwardly of their outer or free ends, said arms 12a are provided with the inwardly disposed parts 14, such as pins which are also disposed through the slots 9 of the arms 8.

35 55 When the member R is in its lowermost posi-

tion, the arms 8 are also in their lowest positions with their free ends rearwardly disposed. When the member R is initially at its lowered position, the intermediate or base 12 will be spaced from the adjacent rear edge wall of the seat A whereupon the seat A is moved forwardly to bring the intermediate or base portion 12 into close proximity to the rear portion of the edge wall of the seat A whereby said rear edge wall serves to hold the member R against raising and to assure desired accommodation of the seat A and member R within the groove 2.

The slots 9 permit the desired forward movement of the seat member R and also the required rearward movement when the seat A is lowered upon the seat S and it is desired to raise the member R into working or effective position. The extent of rearward shifting or movement of the member R must be sufficient to allow the member R or more particularly the intermediate or base portion 12 thereof to freely pass over and beyond the rear edge face of the seat A.

The limit of forward movement of the member R is determined by contact of the arms 8, as they swing upwardly and forwardly, with the front end walls a of the recesses 6 and which is preferably when the arms 8 are substantially perpendicular to the seat A.

The base or intermediate portion 12 of the member R at the central rear part thereof is provided from below with a recess 16 extending transversely of the seat A and which is adapted to house a leg 17 which, when extended, coacts with both the seat A and the raised member R to provide a prop for the rear portion of the raised member R.

The leg 17 is herein disclosed as flat and has one end portion pivotally mounted, as at 18, within the recess 16 adjacent to an end thereof so that when dropped or lowered to serve as a prop, said leg will contact with an adjacent end wall b of the recesses 16 to limit the extent of such dropping or lowered movement which is preferably when the leg 17 is at right angles to the seat S.

The portion 19 of the inner wall of the lid or cover C defined by the groove 2, is preferably removable so that the space enclosed by the inside wall c of the groove 2 may be used as a storage space.

When the member R is moved rearwardly to the extent afforded by the slots 9 of the arms 8, the inwardly disposed parts or pins 14 will be in position to pass through the lateral slot extensions 9 for seating within the pockets 11 so that when the member R is fully raised the front portion thereof will be properly supported. Upon lowering of the leg 17, the contact of the same with the adjacent rear portion of the seat will afford proper support for the raised rear portion of the member R.

From the foregoing description it is thought to be obvious that a toilet seat constructed in accordance with my invention is particularly well adapted for use by reason of the convenience and facility with which it may be assembled and operated.

I claim:

1. In combination, a toilet seat, a substantially U-shaped member straddling the seat from the rear when in lowered position, rigid links pivotally connected with the forward portions of the member and the adjacent portions of the seat, the pivotal connection between each of the links and member comprising a slot in one and a part carried by the other working in said slot.

2. In combination, a toilet seat, a substantially U-shaped member straddling the seat from the rear when in lowered position, rigid links pivotally connected with the forward portions of the member and the adjacent portions of the seat, the pivotal connection between each of the links and the member comprising a slot in the link and a part carried by the member working in the slot.

3. In combination, a toilet seat, a substantially U-shaped member straddling the seat from the rear when in lowered position, rigid links pivotally connected with the forward portions of the member and the adjacent portions of the seat, the pivotal connection between each of the links and member comprising a slot in one and a part carried by the other working in said slot and means for limiting the upward swinging movement of the links.

4. In combination, a toilet seat, a substantially U-shaped member straddling the seat from the rear when in lowered position, rigid links pivotally connected with the forward portions of the member and the adjacent portions of the seat, the pivotal connection between each of the links and member comprising a slot in one and a part carried by the other working in said slot, the side portions of the seat having recesses to house the links when in their lowermost positions.

5. In combination, a toilet seat, a substantially U-shaped member straddling the seat from the rear when said member is in lowered position, link and pin means coupling the U-shaped member at each of its opposite sides with the seat permitting back and forth movement of the member when the member is in its lower position, said pin means being carried by the member and each link having a longitudinal slot terminating in a lateral offset at one end, in which the adjacent pin slides, each link at the opposite end of the slot being pivoted for vertical swinging.

ROSE LIEBLING.
